UNITED STATES PATENT OFFICE.

JOHN M. SHIMER, OF WILKINSBURG, PENNSYLVANIA, ASSIGNOR TO WILSON-SNYDER MANUFACTURING COMPANY, A CORPORATION OF PENNSYLVANIA.

PUMP.

Application filed April 13, 1927. Serial No. 183,356.

This invention relates to pumps and more particularly to an improved system for lubricating the valve operating mechanisms of such pumps as, for example, slush or mud pumps commonly employed in the oil fields for pumping the slush from a well during drilling or for pumping any other heavy, viscous material desired.

Due to the extremely hard usage to which pumps of this class are subjected those lubricating systems employing reservoirs on moving parts are unsatisfactory for the reason that such reservoirs are easily damaged, their covers become warped or lost so as to admit dirt or other material to the lubricant and the system shortly becomes ineffective.

An object of this invention is to provide a pump of the type set forth having an improved lubricating system for the valve operating mechanism.

A further object is to provide a lubricating system for the purpose set forth of such construction and arrangement as to form a substantially closed system from which dirt and the like is effectively excluded.

A still further object is to provide an arrangement of the type described which will be rugged and simple in construction, reliable in operation and cheap to manufacture and assemble.

These and other objects which will be apparent to those skilled in this particular art are accomplished by means of the invention illustrated in the accompanying drawings, in which Figure 1 is a side elevation of a duplex pumping unit constructed in accordance with one embodiment of this invention. Fig. 2 is a similar view on an enlarged scale of certain parts thereof; and Fig. 3 is a sectional view on the line 3-3 of Fig. 2.

The particular embodiment of this invention which has been chosen for the purposes of illustration is shown in connection with a duplex pumping unit 5 having the usual parallel piston rods 6 and 7 operating between the steam end 8 and the liquid end 9 of the pump. The valve chest 10 has the usual steam controlling valves (not shown) which are operated separately by individual valve stems 11 extending outwardly from the valve chest in the usual manner. As is common in duplex units, the valve stem for operating the steam valve of one cylinder is actuated by movement of the piston rod associated with the other cylinder.

A housing 12 is mounted upon the unit and supports two vertically spaced rocker shafts 13 and 14. The upper shaft is oscillated by an actuating lever 15 having a bell-shaped hub 16 secured to the shaft and the opposite end of the lever is provided with a roller 17 received within a cross head 18 secured to the associated reciprocating piston rod 7. The opposite end of the upper rocker shaft 13 has a crank 19 having a bell-shaped hub 20 secured to the shaft. The crank 19 is bifurcated, see Fig. 3, and is connected to the associated valve stem 11 by a connecting link 21 of special form. The connecting link includes a channeled link head member 22 which is secured within the bifurcations of the crank by a suitable securing pin 23. The link head member is provided with a lubricant channel 24, see Fig. 3, communicating with the interior of a hollow pin 25, the opposite end of which is secured to a second link head 26 having a bore 27 communicating with the interior of the hollow pin and leading to a pin 28 connecting the head 26 with the associated valve stem 11.

The bell-shaped hub of the crank 19 is provided with an annular lubricant channel 29 and a hole 30 is drilled through the hub so as to form a passageway for lubricant from the channel 29 to the bifurcated crank 19. The bell-shaped hub 16 of the valve mechanism operating lever 15 is provided with a similar annular channel 31 forming a lubricant passageway and a drilled hole 32 leads from this passageway to a lubricant conveying tube 33 mounted within a groove 34 in the inner face of the lever. The tube extends downwardly to the roller connection 17 between the lever and the associated piston rod cross head 18 for the purpose of conveying lubricant to the connection.

A lubricant reservoir 35 of substantial size is mounted on the pump unit and communicates with the bearing for the upper rocker shaft 13 through a suitable valve controlled pipe 36.

The lower rocker shaft 14 is oscillated by an actuating lever arm 37, the lower end of which is connected to the associated piston rod 6 by a roller 38 received within the cross head 39 secured to the rod. This lever has a bell-shaped hub 40 secured to the lower rocker shaft and provided with an annular channel 41 forming a lubricant passageway

- from which lubricant flows to the roller 38 through a drilled opening 42 in the hub communicating at one end with the annular channel and at the other with a lubricant tube 43 mounted in a groove 44 in the inner face of the lever. The opposite end of the lower rocker shaft is provided with an upwardly extending bifurcated crank 45 having a bell-shaped hub 46 secured to the shaft. 5 The crank 45 is connected to the associated valve stem by a connecting link having a channeled link head member 47 and similar in all respects to the connecting link 21. A lubricant opening 48 is formed in the hub 10 of the lever 15 for the purpose of supplying lubricant to the channeled link head 47 from the lubricant passageway 32 in the lever hub 16. Lubricant is conveyed from the reservoir 35 to the bearing for the lower rocker shaft through a valve controlled pipe 49.

It will be readily apparent that lubricant flows from the reservoir 35 through the pipe 36 to the upper rocker shaft 13 within the 15 housing 12 and along this shaft in one direction to the bell-shaped hub 16 of the valve actuating lever 15 where it is received within the passage formed by the annular channel 31 and from which it flows through 20 the passage 32 and tube 33 to the roller 17 connecting the lever to the associated piston. A part of the lubricant within the passage 32 will flow through the hole 32 into the interior of the channeled link head member 35 48 so as to lubricate the entire connecting link assembly. Lubricant will also flow in the other direction along the rocker shaft 13 to the bell-shaped hub 20 of the crank 19 at the opposite end of the shaft from the 40 operating lever 15 through the passageway formed by the channel 29 and opening 30 to the channeled link head member 22 so as to lubricate the pin 23 connecting such member to the crank 19. The elongated channels 45 provided in the respective link head members 22 and 47 form, in effect, secondary reservoirs from which lubricant flows through the associated hollow connecting links 25 and link head members 26 to the pins 28 connecting the latter to the respective valve stems 11. 50

Lubricant also flows from the reservoir 35 through the pipe 49 to the lower rocker shaft 14 within the housing 12 and through the bell-shaped hub 40 of the associated valve 55 operating lever 37, through the passageway formed by the annular channel 41 and hole 42 to the tube 43 and thence to the roller 48 connecting the lever to the cross head 39 on the valve stem 6.

It will be apparent that the present invention provides a lubricating system for the valve mechanism of such character as to be substantially a closed system into which it is practically impossible for dirt or other 60 matter to penetrate even under the most ar-

duous use. The arrangement is such that a reservoir of considerable capacity can be employed and the lubricant is positively conveyed to each of the moving parts.

Although I have described what I now consider to be the preferred embodiment of this invention it will be apparent that various changes, additions, substitutions and omissions can be made therein without departing from the spirit of this invention or the scope of the appended claims.

What I claim as new and desire to secure by Letters Patent is:

1. The combination in a pump having a valve operating mechanism including a lever mounted on a pivotal support, a piston rod, a connection between said rod and said lever for oscillating said lever, means for supplying lubricant to said support and a passage for conveying lubricant from said support to said connection.

2. The combination in a pump having a valve operating mechanism including a lever mounted on a pivotal support, a piston rod provided with a cross head, a roller on said lever cooperating with said cross head, means for supplying lubricant to said support and a closed connection extending along said lever for conveying lubricant from said support to said roller.

3. The combination in a pump having a valve operating mechanism including an operating lever, a shaft supporting said lever, a connection between said lever and the piston of said pump for operating said lever, a valve stem and a connection including a hollow link between said valve stem and said lever, means for supplying lubricant to said shaft, passages for conveying lubricant from said shaft to said hollow link and a passage for conveying lubricant from said shaft to said piston connection.

4. The combination in a pump having a valve operating mechanism including a rocker shaft and a valve stem, a connection between said shaft and said stem including a hollow link, a securing pin at each end of said link and passages for conveying lubricant from said shaft to the interior of said hollow link for supplying lubricant to said pins.

5. The combination in a pump having a valve operating mechanism including a rocker shaft, a valve stem, a crank on said shaft, a connection between said stem and said crank including a hollow link head secured to said crank, a second link member secured to said stem, a hollow member connecting said link members, a reservoir for supplying lubricant to said shaft and passages extending through said crank for conveying lubricant from said shaft to said links.

6. The combination in a pump having parallel piston rods and a valve mechanism

adapted to be actuated thereby, of separate vertically spaced rocker shafts, a lever secured to each of said shafts and provided with a roller for cooperating with a cross head on the associated piston rod for rocking said shafts, a valve stem connected to each rocker shaft, means for supplying lubricant to each of said rocker shafts, passages associated with each lever for conveying lubricant from the associated shaft to each roller, passages for conveying lubricant from said upper shaft to its valve stem connection and a by-pass for conveying lubricant from said upper shaft to the valve stem connection of said lower shaft.

7. The combination in a pump having a valve operating mechanism including a lever having a hub mounted on a pivotal support, a piston rod provided with a crosshead, a roller on said lever co-operating with said cross head, means for supplying lubricant to said support, a lubricant conveying passage extending along said lever for conveying lubricant to said roller and a passage extending through said hub for conveying lubricant from the supply in said support to said first named passage.

8. The combination in a pump having a valve operating mechanism including a le-

ver, a shaft supporting said lever, a valve stem and a connection including a hollow link between said valve stem and said lever, means for supplying lubricant to said shaft and passages extending through said lever for conveying lubricant from said shaft to said hollow link.

9. The combination in a pump having parallel piston rods and a valve mechanism adapted to be actuated by each of said rods, of separate rocker shafts, a lever secured to each of said shafts and having a connection with an associated piston rod so as to rock said shafts, a valve stem associated with each of said shafts, a connection between each stem and the associated shaft, mechanism for supplying lubricant to each shaft, passages for conveying lubricant from one shaft to the connections between each shaft and each associated valve stem, passages for conveying lubricant from said shaft to the associated piston connection and passages for conveying lubricant from the other of said shafts to the associated piston connection.

In testimony whereof, I have hereunto subscribed my name this 11th day of April, 1927.

JOHN M. SHIMER.
